UNITED STATES PATENT OFFICE.

FREDERIC E. FARWELL, OF FITCHBURG, MASSACHUSETTS.

VICE.

SPECIFICATION forming part of Letters Patent No. 400,069, dated March 26, 1889.

Application filed October 4, 1888. Serial No. 287,185. (No model.)

To all whom it may concern:

Be it known that I, FREDERIC E. FARWELL, of Fitchburg, in the county of Worcester, State of Massachusetts, have invented a certain new and useful Improvement in Vises, of which the following is a description sufficiently full, clear, and exact to enable any person skilled in the art or science to which said invention appertains to make and use the same, reference being had to the accompanying drawings, forming part of this specification, in which—

Figure 1 is a bottom plan view of my improved vise, a portion of the movable jaw and block being shown as broken away; Fig. 2, a vertical transverse section taken on line *x x* in Fig. 1; Fig. 3, a horizontal section taken on line *y y* in Fig. 2, the jaws being represented as broken off; Fig. 4, a side elevation of the sliding block removed; Fig. 5, a horizontal section taken on line *z z* in Fig. 4, and Fig. 6 a perspective view of one of the wedge-blocks removed.

Like letters and figures of reference indicate corresponding parts in the different figures of the drawings.

My invention relates to that class of vises known as "bench-vises;" and it consists in certain novel features, as hereinafter fully set forth and claimed, the object being to produce a simpler and more effective device of this character than is now in ordinary use.

The nature and operation of the improvement will be readily understood by all conversant with such matters from the following explanation.

In the drawings, A represents the fixed jaw, B the movable jaw, and C the hand-wheel. The fixed jaw comprises a vertically-arranged jaw proper, D, and an attaching-plate, A', adapted to be secured to the bench by screws inserted in screw-holes *b*. The under side of the fixed jaw A is provided with a longitudinally-arranged groove, *d*, forming a track or way in which the movable jaw B slides. The movable jaw comprises a jaw proper, H, which registers with the jaw proper, D, when in use, and a box-shaped body or frame, B', provided with longitudinally-arranged flanges *f* on its upper edge adapted to enter the

grooves *d* in the fixed jaw. A longitudinally-arranged rod, K is disposed centrally in the body of the movable jaw, said rod being fitted to revolve therein without being withdrawn therefrom, and provided with the hand-wheel C on its outer end. The rod K is screw-threaded at *g*, and fitted to travel on said threaded portion is an interiorly screw-threaded nut, *h*. The sides of the body of the movable jaw are provided with longitudinal slots or openings *i*, and the sides of the nut *h* with horizontally-arranged grooves *k*, (see Figs. 4 and 5,) adapted to register with said slots, the bottom of said grooves being inclined, as shown at 1 in Fig. 5. Disposed in each groove *k* is a wedge-shaped block, *m*, having one face, *p*, (see Fig. 6,) inclined to correspond with the inclined bottom of said groove, the opposite face of said block being provided with serrations *r* and a longitudinal groove, *t*, in which is secured an oval-shaped spring, *v*. (See Figs. 1 and 3.) The wedge-block *m* is of such width that when in position in the groove *k* it projects into the slot *i* in the body of said jaw and its spring *v* engages the flange 15 of the track *d* on the fixed jaw.

In the use of my improvement, the fixed jaw being secured to the bench and the movable jaw disposed in the track *d* of said fixed jaw, when it is desired to clamp an article between the jaws proper, H D, the movable jaw is pushed inward on said track until said jaws proper engage the article. The hand-wheel C is then turned from left to right, causing the nut *h* to advance on the rod K and force the serrated face *r* of the wedge-blocks *m* into engagement with the flange 15 of the fixed jaw, thereby securely clamping the movable jaw against the article in the vise. When the hand-wheel is turned back, the nut *h* retreats on the rod K and the wedge-blocks are disengaged from the fixed jaw, the springs *v* forcing said blocks back into the grooves *k* and preventing them from accidentally binding against the flange 15, thus enabling the movable jaw to be easily withdrawn in the track *d*.

The edges of the flange 15 may be serrated or roughened, if desired, to prevent the

wedge-blocks from slipping when the article in the vise is subject to sudden blows; but I do not confine myself to so doing.

Having thus explained my invention, what 5 I claim is—

The combination of a fixed jaw having an attaching-plate provided with ways, a movable jaw provided with a box-shaped flanged frame adapted to slide in said ways and having slots in its sides, a rod journaled in the ends of said frame and provided with a screw-thread near its inner end, a nut adapted to travel on said rod and provided with inclined

grooves in its opposite faces, wedge-blocks disposed in said grooves and projecting into 15 said slots, the outer faces of said blocks being serrated and provided with recesses, and laterally-expanding springs adjusted in said recesses and bearing upon the edges of said ways for forcing said blocks inward, substantially as described. 20

FREDERIC E. FARWELL.
